FIG. 1.

FIG. 2.

INVENTOR
EDWARD B. GOLDEN
BY *Ed. B. Golden*
ATTY.

UNITED STATES PATENT OFFICE.

EDWARD BENSON GOLDEN, OF HAMILTON, ONTARIO, CANADA.

MOP.

1,358,076.

Specification of Letters Patent.

Patented Nov. 9, 1920.

Application filed June 24, 1919. Serial No. 306,329.

To all whom it may concern:

Be it known that I, EDWARD B. GOLDEN, a subject of the King of Great Britain, residing at Hamilton, in the county of Wentworth and Province of Ontario, Canada, have invented certain new and useful Improvements in Mops, of which the following is a specification.

My invention relates to improvements in handle mops, and more particularly to an improved mechanism for detachably securing the mop cloth to the handle, and consists essentially of a rigid and a pivotal jaw for engaging the mop cloth therebetween, and a resilient member rigid with the pivotal jaw and extending upward and adapted to yieldably embrace the handle and to cause the said pivotal jaw to clamp the cloth against the rigid jaw by tensional pressure.

20 The invention has for its objects, to provide a simplified and inexpensive device of the class specified, that will be durable, efficient and easily operated.

These, together with other aims of the invention, may be obtained by the combination, construction, and arrangement of the parts as will be hereinafter more fully described, illustrated in the accompanying drawing, and pointed out in the claims 30 hereunto appended.

Reference may now be had to the accompanying drawing, in which:—

Figure 1 is a front elevation of the improved device; and,

35 Fig. 2 is a side elevation of the same.

Fig. 3 is an enlarged detailed view of the movable jaw.

Similar reference characters refer to similar parts throughout the several views.

40 The mop handle is indicated by A. B is a plate having pressed therefrom a plurality of alternately opposed semi-circular integral members 2 arranged in staggered relation, wherein is inserted the said handle, 45 the end of which is tapered to assure a tight fit.

The plate B is deflected at an angle extending downward forming a jaw 3. A resilient wire C is bent at right angles at 50 both ends to form journals 4 pivoted in brackets 6 rigid on the side of said plate opposite to that in which the jaw 3 is deflected from. The said brackets are located on said plate just above the jaw 3, and adjacent to the lateral edges of the plate.

The intermediate length of the wire C extends in parallel relation to its journals 4, in a downward direction substantially paralleling the jaw 3, and after passing the termination of the jaw curves upwardly at 5 60 and is deflected inwardly to a closer parallel relationship at 7. The space between the two related portions of the wire at this point is a trifle wider than the diameter of the handle A, and these portions 8 of the 65 wire intersect the handle diagonally at 9 in a slight degree S curve, one portion on either side of the handle.

The wire now curves abruptly at 10 and again intersects the handle at 11, after which it is bent in horseshoe formation around the handle, as clearly shown in Fig. 1, and indicated by 12. Between the aforesaid abrupt curve 10 and the handle, the two portions of wire are bent inwardly at 13 so that the 70 space between at that point is less than the diameter of the handle and it is provided at each end with a pair of extended portions, which are bent around the two portions of wire C, thereby holding the same rigid therewith.

A jaw 14 is secured at each end to the two portions of wire C, and tensionally engages the mop cloth D against the jaw 3, when the wire is in the position hereabove set forth. 75 The jaw 14 is angular or L shaped in cross section to constitute double contact edges.

To release the cloth, the wire C is swung to a position as indicated in chain lines in Fig. 2, the bent in portions 13 of the wire 90 being yieldably and forcibly passed by the handle.

To clamp the cloth between the two jaws, the above described operation is reversed.

Having now fully described my invention, 95 what I claim and desire to secure by Letters Patent of the United States, is:—

1. In a device of the class described, the combination with a handle, of a jaw rigid with the handle, a pivotal jaw, a resilient member rigid with the pivotal jaw, passing around the lower edge of said rigid jaw and extending upward on the side of the same opposite to that upon which is the pivotal jaw, and means for yieldably retaining said member in the aforesaid position. 100

2. In a device of the class described, the combination with a handle, of a jaw rigid with the handle, a pivotal jaw coacting with the rigid jaw, a resilient member rigid with 105

110

the pivotal jaw, passing around the lower edge of said rigid jaw and extending upward on the side of the same opposite to that upon which is the pivotal jaw, and a forcibly expandible horseshoe shaped member in said resilient member yieldably engaging the handle.

3. In a device of the class described, the combination with a handle, of a jaw rigid with the handle, a pivotal jaw coacting with the rigid jaw, a resilient wire rigid with the pivotal jaw, passing around the lower edge of said rigid jaw and extending upward on the side of same opposite to that upon which is the pivotal jaw, diagonally intersecting said handle, then bent abruptly forward, the central and uppermost portion of the wire being in horseshoe formation encircling the handle, the opening of the horseshoe portion being narrower than the diameter of the handle, the wire at that part being forcibly expandible.

4. In a device of the class described, the combination with a handle, of a plate rigid

with the handle, an integral jaw extending downward at an angle from said plate, a resilient wire bent at its ends to form journals said journals being pivoted in brackets rigid on said plate adjacent to its lateral edges, a second jaw rigidly secured to said wire and adapted to co-act with the first wire and disposed parallel therewith, said wire passing around the lower edge of said rigid jaw and extending upward on the side of said plate opposite to that upon which are pivoted said journals, diagonally intersecting said handle, then bent abruptly forward, the central and uppermost portion of the wire being in horseshoe formation encircling the handle, the opening of the horseshoe portion being narrower than the diameter of the handle, the wire at that part being forcibly expandible.

In testimony whereof I have affixed my signature.

EDWARD BENSON GOLDEN.

Witness:

H. G. HENDRY.
